US00D892058S

(12) **United States Design Patent** (10) **Patent No.:** **US D892,058 S**
(45) **Date of Patent:** **** Aug. 4, 2020**

(54) **ELECTRICAL CONNECTOR**

(71) Applicant: **Amphenol Corporation**, Wallingford, CT (US)

(72) Inventors: **Marc B. Cartier, Jr.**, Dover, NH (US); **Mark W. Gailus**, Concord, MA (US); **David Levine**, Amherst, NH (US); **Vysakh Sivarajan**, Nashua, NH (US); **John Robert Dunham**, Windham, NH (US); **John Pitten**, Merrimack, NH (US)

(73) Assignee: **Amphenol Corporation**, Wallingford, CT (US)

(**) Term: **15 Years**

(21) Appl. No.: **29/666,525**

(22) Filed: **Oct. 12, 2018**

(51) LOC (12) Cl. **13-03**

(52) U.S. Cl.

(57) **CLAIM**

The ornamental design for an electrical connector, as shown and described.

DESCRIPTION

FIG. 1 is a top, front, left side perspective view of an electrical connector showing a first embodiment of our new design;

FIG. 2 is a top, rear, right side perspective view thereof; FIG. 3 is a cutaway top, front, left side perspective view thereof;

FIG. 4 is a front elevation view thereof;

FIG. 5 is a rear elevation view thereof;

FIG. 6 is a left side elevation view thereof;

FIG. 7 is a right side elevation view thereof;

FIG. 8 is a top plan view thereof;

FIG. 9 is a bottom plan view thereof.

FIG. 10 is a top, front, left side perspective view of a second embodiment thereof

FIG. 11 is a top, rear, right side perspective view of FIG. 10;

FIG. 12 is a front elevation view of FIG. 10;

FIG. 13 is a rear elevation view of FIG. 10;

FIG. 14 is a left side elevation view of FIG. 10;

FIG. 15 is a right side elevation view of FIG. 10;

FIG. 16 is a top plan view of FIG. 10; and,

FIG. 17 is a bottom plan view of FIG. 10.

The dash-dot-dash broken lines represent boundaries of the electrical connector and form no part of the claimed design. All other broken lines represent portions of the electrical connector that form no part of the claimed design.

1 Claim, 17 Drawing Sheets
